UNITED STATES PATENT OFFICE

FREDERICK W. VODOZ, OF CHICAGO, ILLINOIS, ASSIGNOR TO GOODMAN MANUFACTURING COMPANY, OF CHICAGO, ILLINOIS, A CORPORATION OF ILLINOIS

DEVICE FOR HANDLING LOOSE MATERIALS

Application filed August 6, 1927. Serial No. 211,191.

This invention relates to improvements in devices for handling loose material, and has as its object to provide a machine which will cheaply and efficiently remove draw slate 5 from a mine roof.

Many bad mine roofs are caused chiefly from the fact that the roof directly above the coal seam is composed of a draw slate. This draw slate varies in thickness from a few inches to several feet and disintegrates and falls from the main mine roof on being exposed to the air. This usually occurs right after the coal has been shot down before it has been loaded and thus makes it necessary to separate this draw slate from the coal by hand at the face while the coal is being loaded, in order to get a clean product. This is an expensive operation both to the miner and operator, and renders the use 20 of loading machines impossible since no loading machine can sort the dirt from the coal. At times this draw slate clings to the main roof after the coal has been loaded but later falls without warning. It may be seen 25 that great damage may be caused by the falling of this draw slate and that it is liable to injure the workmen as well as cause a great deal of expense and loss of time.

The device constituting my invention will 30 economically remove and load this slate by machine before the coal has been mined and thus eliminate this dangerous and costly condition and make it possible to safely load the clean coal either by machine or hand.

My invention may be best understood by 35 referring to the following drawings wherein:

Figure 1 is a side elevation of the device 40 embodying my invention in operative position with portions broken away to more clearly show the details of construction;

Figure 2 is a top plan view of the device 45 shown in Figure 1;

Figure 3 is an enlarged top plan view of 50 the device shown in Figure 1 with portions broken away to more clearly show the details of construction;

Figure 4 is a side elevation of the device 55 shown in Figure 1 in a position ready to travel about the mine;

Figure 5 is a sectional view taken on line 5-5 of Figure 1;

Figure 6 is a sectional view taken on line 6-6 of Figure 1, and

Figure 7 is an enlarged view showing the 55 details of the flexible material gathering devices.

Referring now to the drawings, and more particularly to Figures 1 and 2, it may be seen that I have provided a plurality of 60 flexible material handling devices 10, 10, insertible in a kerf 11 in the usual manner, after it has been cut by a mining machine just beneath the slate top. After the kerf has been cut the slate top is shot down by 65 powder where it rests on the flexible material handling devices 10. A winding drum 12 is provided to remove these flexible material handling means, one at a time, with the slate thereon. 70

Each of the flexible material handling devices 10 comprises a portion 13 of any suitable heavy flexible material such as the material used in heavy canvas or composition belting. The inner end of the portion 13 is 75 adapted to be fastened to the drum 12 by any suitable means while the other end has an upturned portion 14 to catch the loose material and draw it out with the portion 13, and also to aid in inserting this material gathering means into the kerf. The means herein used for fastening the inner end of the portion 13 to the drum 12 consists of a metal portion 13^a on the end of the portion 13. This end portion is turned over to fit in a 80 slot 13^b in the drum 12 to hold the device 85 10 so it may be wound in by the drum 12.

It may be noted that since the material gathering devices 10, 10, overlap when inserted in the kerf, that the upturned portion 90 14 does not extend the full width of its respective portion 13 but only extends to the overlapping portion of the adjacent material gathering device. These material gathering devices are inserted in the kerf with 95 the aid of a long pole or any other suitable means of like nature.

Referring now more particularly to the gathering and loading machine itself, it may be seen that I have provided a frame or 100

body portion 15 slideable on its bottom on the mine bottom or capable of travelling by itself along the mine rails. Studs 16 project outwardly from each side of the forward portion of the body portion 15 and suitable track wheels 17 may be placed thereon when it is desired to travel about the mine on the mine rails. An axle 18 is journaled in the rearward portion of said body portion and has track wheels 19, 19 which may be keyed thereto when it is desired to travel about the mine on the rails. The wheels 19 serve as driving rails for the device.

Said frame portion 15 has mounted thereon the drum 12 for winding in the material handling means 10, an auxiliary conveyor 20 for handling the material discharged from the material handling devices 10, 10, a rope drum 21 for moving the frame 15 along the mine floor on its bottom, and a suitable driving motor 22 for providing motive power to drive the frame along the mine or along the mine rails and to actuate the winding drum 21 and the conveyor 20.

The material handling devices 10, 10, are supported on a plate 24 projecting forwardly from the winding drum 12 to the mine wall where its forward end engages said mine wall during the loading operation (see Figure 1). The rearward portion of the plate 24 has lugs 25 projecting outwardly from each end thereof which are journaled in the upper portion of supports 26. The lugs 25 are hollow and serve as bearings for a shaft 27 which has the winding drum 12 keyed thereon. It may here be seen that the supports 26 serve to support the winding drum 12 and supporting plate 14 and are journaled in a support 29 at 29^a. The support 29 projects upwardly from the frame 15 and is integral therewith. A portion of the support 26 projects downwardly from the point 29^a where said support is journaled in the support 29 and has a forked end portion 30 to receive a threaded sleeve 31 having a trunnion 32 projecting from each side thereof which fit in slots 33 in the forked end portion 30. A threaded shaft 34 is threaded through lugs 35 projecting outwardly from the portion 29 and is also threaded through the threaded sleeve 31. A hand wheel 36 is provided to rotate said shaft and move the threaded sleeve 31 longitudinally on said shaft and thus move the supports 26 about their pivotal point to raise or lower the drum 12 and supporting plate 24 to accommodate said drum and supporting plate to the various heights of kerfs which may be encountered and to lower said mechanism so as to take up as little head room as possible while traveling about the mine.

A pair of adjustable supporting means 38 indicated generally at 38 support the for-

ward end of the supporting plate 24 to support said plate at various heights for the different heights of kerf encountered. The adjustable supporting means 38 is a simple screw supporting means comprising a screw 39 threaded in a support 41 projecting from the portion 29 and having a socket 42 at its upper end abutting and supporting the supporting plate 24. A handwheel 43 is provided to rotate the screw 39 and adjust the supporting plate 24.

The drive connection from the motor 22 to the winding drum 12 comprises a bevel motor pinion 44 which drives a bevel gear 45 keyed to a vertical shaft 46. A worm 47 keyed to the shaft 46 and driven therefrom meshes with a worm gear 48 to rotate a shaft 50. A sprocket 51 is freely mounted on said shaft and selectively connectible therewith by a suitable jaw-clutch generally indicated at 52. A transverse shaft 53 journaled in the supports 26 is driven by the sprocket 51 through a sprocket 54 and drive chains 55. Another sprocket 56 is keyed to the outer end of the shaft 53 and drives a sprocket 57 on the shaft 27 through a drive chain 58 to drive said shaft and the winding drum 12 which is keyed thereto.

The conveyor 20 is pivotally mounted for rocking movement on an auxiliary frame 60 at 61. The frame 60 is in turn mounted for pivotal movement around a vertical axis on the frame 15 and is supported for said pivotal movement on studs 64 and 65 integral with the frame 15. The rocking movement of the conveyor 20 is controlled by a pair of adjusting screws 66 on each side near the forward end thereof. Said adjusting screws are threaded in supports 67 projecting from the frame 60 and have threaded sleeves 68 thereon with trunnions projecting therefrom and received in slotted members 69 projecting to each side of the conveyor 20 and parallel thereto. Hand wheels 70 are provided to rotate said adjusting screws and vary the height of discharge of the conveyor 20.

The conveyor 20 is a continuous belt conveyor of an ordinary design with flights 71 thereon. Said conveyor is driven by the motor 22 in all positions of vertical or horizontal adjustment thereof through a suitable drive means comprising a pinion 72 keyed to the lower portion of the vertical shaft 46 and driven therefrom. A spur gear 73 is driven by said pinion and in turn drives a vertical shaft 74. This shaft is journaled in the bottom portion of the frame 15 and in the central portion of the studs 64 and 65 on which the frame 60 and conveyor 20 rotates. A bevel pinion 75 is keyed to the shaft 74 and drives a bevel gear 76 on one end of a shaft 77. Another bevel pinion 78 is keyed to the opposite end of said shaft and drives a bevel gear 79.

The bevel gear 79 is freely mounted on a shaft 80 and is connectible therewith through a jaw clutch generally indicated at 81. A sprocket 82 is keyed to the opposite end of said shaft and drives a sprocket 83 keyed to the shaft 84 through a drive chain 85 to drive the conveyor 20.

The apparatus above described is moved on its bottom along the mine bottom by means of the rope drum 21 which is freely mounted on the shaft 50 and selectively driven therefrom by a friction cone clutch generally indicated at 86. Suitable rollers and pulleys are provided to lead the rope over the forward or rearward ends or to either side of the machine.

A squared shank 87 is provided on one end of the shaft 50 to provide a means for driving said apparatus along the mine rails on the removable track wheels 17 and 19. A sprocket 88 is attachable to said squared shank to drive a sprocket 89 fixed to a rear wheel 19 by a drive chain 90 and thus drive the wheels 19 and move my device along the mine rails from working place to working place.

From the foregoing description it may be seen that I have provided a machine which is a complete unit for removing and loading slate from the mine roof, and that said unit is self-propelled either on rails or on the mine bottom.

The loading operation is simple and efficient; for as has been explained it may be seen that the flexible material handling devices 10 may be placed in the kerf 11 for the whole length of the cut and that after the roof has been shot down these flexible material handling means 10 may be removed one at a time by the device described herein. The first material handling device 10 in the kerf 11 is fastened to the drum 12 and slowly wound on said drum taking the slate with it from the kerf and discharging said slate on the conveyor 20 which in turn discharges said slate in the gob or in a suitable mine car. This operation is repeated until all of the material handling devices 10 are pulled from the kerf. The machine is moved along the face of the coal from one material handling device to another by means of a draft rope 86 wound on the rope drum 21. Thus it may be seen that with one cutting and shooting operation the apparatus herein described can remove and load the slate from the entire working face and that while one working face is being loaded another working face may be made ready to be loaded to keep the loading operation continuous.

While I have shown and described one form in which my invention may be embodied, it will be understood that the construction and arrangement of the various parts may be altered or changed without

departing from the spirit or scope thereof. Furthermore, I do not wish to be construed as limiting myself to the particular embodiment illustrated, excepting as it may be limited in the appended claims.

70

I claim as my invention:

1. In a device of the class described, a body portion slideable on a mine bottom, a winding drum adjustably supported near the forward end thereof, a supporting plate projecting forwardly from said drum adaptable to engage a mine wall, and a flexible material handling device insertible in a kerf in a mine wall, supported on said supporting plate and adaptable to be wound in by said drum over the top portion thereof for removing said material handling device from said kerf loaded with loose material.

2. In a device of the class described, a body portion slideable on a mine bottom, a winding drum adjustably supported near the forward end thereof, a supporting plate projecting forwardly from said drum adaptable to engage a mine wall, and a flexible material handling device insertible in a kerf in a mine wall, supported on said supporting plate and adaptable to be wound in by said drum over the top portion thereof for removing said material handling device from said kerf loaded with loose material.

3. In a device of the class described, a body portion slideable on a mine bottom, a winding drum adjustably supported near the forward end thereof, a supporting plate projecting forwardly from said drum adaptable to engage a mine wall, and a flexible material handling device insertible in a kerf in a mine wall, supported on said supporting plate and adaptable to be wound in by said drum over the top portion thereof for removing said material handling device from said kerf loaded with loose material.

4. In a device of the class described, a body portion slideable on a mine bottom, a winding drum adjustably supported near the forward end thereof, a supporting plate projecting forwardly from said drum adaptable to engage a mine wall, and a flexible material handling device insertible in a kerf in a mine wall, supported on said supporting plate and adaptable to be wound in by said drum over the top portion thereof for removing said material handling device from said kerf loaded with loose material.

5. In a device of the class described, a body portion slideable on a mine bottom, a motor, flexible draft means driven by said motor for moving said device along the mine on its bottom, flexible material handling device insertible in a kerf in a mine wall, a winding drum to wind in said flexible material handling means supported on said supporting frame by a pivotally mounted supporting bracket for vertical adjustment thereof, supporting means for said flexible material handling device projecting forwardly from said drum for engaging a mine wall, a conveyor at the discharge end of said flexible material handling device, and a means for driving said flexible material handling winding drum from the aforementioned motor in all possible positions of adjustment thereof.

6. In a device of the class described, a body portion slideable on a mine bottom, a motor, a winding drum for winding in a flexible draft device for moving the body portion along the mine bottom and driven from said motor, a flexible material handling device insertible in a kerf in a mine wall having a hooked end portion for removing loose material with said flexible ma-

110

130

material handling device as said material handling device is removed from said kerf, a means to remove said flexible material handling device from said kerf comprising a winding drum for winding in said flexible material handling device over the top of said drum, an adjustable support for said drum comprising a bracket pivotally mounted to said supporting frame at a point below said drum having an adjusting means connectible therewith at a point below said pivotal point, and means for driving said supporting device winding drum from said motor in all positions of adjustment thereof comprising a shaft rotatable on the pivotal axis of said bracket connectible with said motor and said winding drum by a suitable driving means.

5. In a device of the class described, a main frame, a flexible material handling device insertible in a kerf in a mine wall, a winding drum supported on said main frame and vertically adjustable with respect thereto, a supporting plate extending forwardly from said winding drum and adaptable to engage a mine wall at various elevations with respect thereto, and means for winding said flexible material handling device on said winding drum and thus removing said flexible material handling device loaded with loose material from said kerf.

Signed at Chicago, in the county of Cook and State of Illinois, this 8th day of August, A. D. 1927.
